UNITED STATES PATENT OFFICE.

ELIAS EDWARDS, OF REMUS, MISSISSIPPI.

VELOCIPED.

SPECIFICATION forming part of Letters Patent No. 256,303, dated April 11, 1882.

Application filed July 11, 1881. (No model.)

To all whom it may concern:

Be it known that I, ELIAS EDWARDS, of Remus, in the county of Leake and State of Mississippi, have invented a new and useful Improvement in Vehicles, of which the following is a full, clear, and exact description.

The object of the invention is to make certain improvements in vehicles operated by the rider, and these will first be described in connection with the drawings, and then pointed out in the claims.

Figure 1 is a side elevation of my invention. Fig. 2 is a plan view thereof. Fig. 3 is a section taken on the line $x x$ of Fig. 2; and Fig. 4 is a detail view, showing my improved means for preventing slipping of the wheels.

Similar letters of reference indicate corresponding parts.

Upon the axles A and A' are placed the springs B B and B', and upon the springs are placed the cross-bars C C', and upon and near the ends of these cross-bars are placed the ends of the upwardly curved, parallel side pieces, D D, which extend beyond the cross-bars C C', and are held together at their forward ends by the cross-piece E. In this cross-piece E, and in that portion of the reach F which extends in front of the forward axle, A', is journaled the vertical post H, to which is secured a short distance above the reach the segment-rack h, which engages with the circular rack h', secured on the upper side of the forward axle.

To the upper end of the post H, above the cross-piece E, is secured the long arm I, which reaches back to the rider, and is adapted to be moved from side to side for guiding the vehicle by the knees of the rider; and in order that the normal position of the forward axle will be such as to cause the vehicle to move in a straight course, I provide the top of the post H with the flat spring o, the ends of which pass between the pins e e' upon the top of the cross-piece E.

The hubs of the rear wheels, K K, are extended inwardly, so as to permit the ratchet-wheels k k and k' k' to be secured upon them, and also to furnish bearings for the rocking levers L L and L' L'. These levers are provided with the spring-actuated pawls i i and

i' i', which engage with the ratchet-wheels k k, which, when the levers are moved or rocked backward and forward, propel the vehicle forward. The levers L' L' are independent of the levers L L, and are to be operated, or rather depressed or forced down, by the feet of the rider, and for this purpose the cross-piece A'', which is attached to the forward extensions of these levers, is placed in convenient reach of the rider. The upward movement of these levers L L is produced by the coiled springs n n, attached to the forward ends of the levers and to the side pieces, D D, above, as shown. The levers L L are operated by the hands of the rider by means of the angle-levers J J, which are pivoted to the side pieces, D D, and connected with the upper ends of the levers L L by the links j j. By this arrangement of the propelling mechanism it will be understood that the vehicle may be propelled either by the hands alone, or by the feet alone, or by both hands and feet, and that the two forces may be applied alternately or simultaneously, as best suits the ease and convenience of the rider.

In order to propel the vehicle backward, I provide the outside of the levers L L with the spring-actuated pawls f f, (shown clearly in Fig. 3,) which are adapted to engage with the ratchet-wheels k' k', and which will cause the power put upon the hand-levers J J to be applied to the rear wheels of the vehicle so as to turn them in a reverse direction. The pawls f f are held out of engagement with the ratchet-wheels k' k' while going forward by the pivoted stops e e, and while going backward the pawls i i and i' i' are held out of engagement with the ratchet-wheels k k by the pivoted stops d d and d' d', (shown in Fig. 3,) all of which stops are operated by suitable rods in reach of the driver.

The construction of the wheels which I propose to use, which will prevent slipping of the wheels under all circumstances, is shown in Figs. 3 and 4. Upon the inside of each spoke of the wheels are secured the sleeves a a, through which the rods b b pass. The lower ends of these rods are bent at an angle and pass through the cam-grooves g g, formed in the annular plate G, which plate is placed upon the hub of the wheel, and is adapted to be partially rotated upon the hub by the rod g' (shown

in Fig. 1) for forcing the rods out to the position shown in Fig. 4 to engage with the ground or to withdraw them to the position shown in Fig. 3, inside the peripheries of the wheels.

5 In a slot made through the reach F is pivoted the lever P, which is connected by the link p to the brake-bar R, which is suspended from the reach F, and the lever P is placed convenient to the seat Q, so that the rider may 10 easily operate the brake with his foot.

In order to regulate the rapidity and force with which the vehicle may be run, I provide the levers L L with the series of holes a' a', into which the ends of the link j may be bolted 15 to shorten or increase the length of the leverage.

Though I have shown my invention applied to a vehicle built upon a small scale to be run by a person, I wish it understood that it may be applied to vehicles of a size adapted to carry 20 a small engine as its motive power, or as a means of supporting and moving large portable engines and the shafting, pulleys, and fly-wheels necessary to attach the same to thrash-

ing or other machinery, and not depart from the spirit of my invention.

In some instances I propose to provide a roughened plate to be attached upon the wheels to prevent slipping, which plates can be attached and removed when desired.

Having thus described my invention, I claim 30 as new and desire to secure by Letters Patent—

1. The levers L L and the independent levers L' L', journaled upon the hubs, and the ratchet-wheels k k, secured upon the hubs, in combination with the angle-levers J J, links j j, and 35 the cross-bar A, whereby the levers may be operated by the hands and feet of the rider, substantially as specified.

2. The annular ring G, formed with the cam-slots g, in combination with the sliding rods 40 b, substantially as and for the purposes set forth.

ELIAS EDWARDS.
